UNITED STATES PATENT OFFICE.

FRANK R. OWENS, OF BEAVER CROSSING, NEBRASKA.

COMBINATION PUMP JACK.

Application filed January 27, 1922. Serial No. 532,313.

To all whom it may concern:

Be it known that I, FRANK R. OWENS, a citizen of the United States, residing at Beaver Crossing, in the county of Seward 5 and State of Nebraska, have invented new and useful Improvements in Combination Pump Jacks, of which the following is a specification.

This invention relates to improvements in a transmitting device, the general object of the invention being to change the movement of an endless traveling member into a reciprocatory motion, so that a pump or the like can be actuated from a rotary member.

Another object of the invention is to provide trip means for reversing the movement of the reciprocatory member at each end of each stroke.

This invention also consists in certain other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the 30 several views, and in which:

Figure 1 is a side view of the invention with parts in section.

Figure 2 is a section on line 2—2 of Figure 1.

35 The remaining figures are detail views.

In these views 1 indicates a casing which is adapted to be suitably supported at the desired location and in which is journaled a pair of shafts 2, one of which is adapted to be connected with any form of power device. 40 Each shaft is provided with a pair of sprockets 3 over which the endless chains 4 pass. The upper shaft is adapted to be adjusted towards or away from the lower shaft so as 45 to adjust the tension on the chains, this adjustment being permitted by making the openings 5, through which the shaft 2 passes, of larger diameter than the shaft and by placing the bearings of the shaft upon the 50 plates 6 which are bolted to the casing. Guides 7 are formed upon the inner faces of the sides of the casing and a plate 8 has its edges engaging said guides. This plate 55 is located between the chains and is provided with an elongated slot 9 through which the

upper shaft 2 passes. A bracket 10 extends from each side of the plate adjacent its lower end to support the ends of a shaft 11 which passes through the plate below the lower end of the slot. Sleeves 12 are rotatably mounted on this shaft, one on each side of the plate and each sleeve is provided with a pair of hook shaped projections 13 which are adapted to be engaged by the rollers 14 which are carried by the chains. These 60 projections 13 are so arranged that the pair on one sleeve will be engaged by the rollers on one chain and the pair on the other sleeve will be engaged by the rollers on the second chain, the rollers on one chain engaging the projections on the upward stroke of the chain and the rollers on the other chain engaging the second pair of projections on their downward movement so that the plate is moved upwardly by one 65 chain and downwardly by the second chain. A pair of lugs 15 project from each side of the plate and each pair slidingly supports a trip rod 16 which is normally held in raised position by the spring 17. A stub shaft 18 70 projects from each side of the plate and a sleeve 19 is rotatably mounted on each shaft. A pair of arms 20 extend from each sleeve and a link 21 connects one arm with the trip rod 16 and a link 22 connects the other 75 arm with an arm 23 on each sleeve 12. These parts are so arranged that when the rollers engage projections 13 the sleeve 12 will be prevented from rotary movement by the link 22 due to the fact that its point of connection with the arm 20 is such that the link 80 will be held against movement. However, as the plate nears the end of its stroke in either direction the trip rod 16 will strike the stationary trip rod 24, one of which is located 85 at each end of the casing, so that the trip rod 16 will be moved longitudinally against the action of its spring and cause the link 21 to rock sleeve 19 and move the pivotal point of link 22 beyond a dead center thus 90 permitting the sleeve 12 to rotate under the pressure of the rollers on the chain to permit the rollers to pass by said projections. Just as soon as these rollers are leaving the 95 projections the rollers on the other chain 100 will come into engagement with the projections on the other sleeve 12 and thus cause the plate to move in an opposite direction. Spring 17 will then move the parts of the 105 disengaged trip rod to normal position. As 110

the plate nears the end of its other stroke the same action will be repeated on the second set of trip rods and their associated parts and then the plate will start on its upward stroke again. As shown in the drawings, each chain carries two pairs of rollers so that the plate will be moved upwardly twice for each revolution of the chain.

10 A connecting rod 26 is pivotally connected with the upper end of the plate by the pin 27. From the above it will be seen that the plate will be given a reciprocatory movement by the movement of the endless chains and this plate can be connected with a pump or the like to actuate the same.

In order to prevent movement of the parts by the strain placed thereon by the chains I connect the plates 6 with lugs 6' formed 20 on the casing by the bolts 6''. These bolts and the nuts will hold the plates against downward movement and said plates can be adjusted, as will be seen, to permit the tension on the chains to be varied.

25 I also provide a bracket 26' on the top of the casing for engaging the rod 26 to stiffen the same when said rod is connected to the pump rod by an arm, such as shown at 26''. In this case the device can be clamped on to the side of the pump.

It is thought from the foregoing description that the advantages and novel features of my invention will be readily apparent.

I desire it to be understood that I may 35 make changes in the construction and in the combination and arrangement of the several parts, provided that such changes fall within the scope of the appended claims.

What I claim is:—

1. An apparatus of the class described 40 comprising an oil tight casing, an endless traveling member therein, a member mounted for sliding movement in the casing, a rock shaft on the reciprocatory member, a projection thereon adapted to be engaged by 45 a part on the endless member, means for holding the rock shaft against movement so as to hold the projection in engagement with the said part on the endless member and trip means for releasing the rock shaft to permit the projection to give under the pressure of the said part. 50

2. An apparatus of the class described comprising a housing, a plate slidably supported therein, rocking members carried by 55 the plate, a projection on each member, means for normally holding the members against rocking movement, trip means at the end of the housing for releasing the locking means so as to permit rocking movement of the rocking members and endless traveling members in the housing having parts thereon for engaging the projections. 60

3. An apparatus of the class described comprising a housing, a plate having sliding 65 movement therein, rock shafts supported by the plate, a projection on each shaft, means for locking the shafts against rocking movement, trip rods for releasing the locking means, a trip device at each end of the 70 housing for engaging the trip rods, a pair of endless traveling members in the housing and parts thereon for engaging the projections.

In testimony whereof I affix my signature.

FRANK R. OWENS.
